MORRIS ROTHMAN AND ESTELLE TANENBAUM ROTHMAN, OF BAYONNE, NEW JERSEY

FIRE ALARM SIGNAL AND PHOTOGRAPHIC APPARATUS

Application filed May 21, 1930. Serial No. 454,310.

This invention relates to a fire alarm signal and photographic apparatus.

The object of the invention is the production of apparatus, which will simultaneously produce an audible signal and a motion picture photograph of a person operating a fire alarm signal box. The second object of the invention is the production of apparatus having electric appurtenances which can be easily connected in electric circuit by existing fire alarm signal boxes. The third object of the invention is the production of apparatus operated with the appurtenances of a fire alarm signal box and which will produce a moving picture exhibiting various views of a person operating the said alarm signal box.

In the accompanying drawings Fig. 1 represents an elevation of the fire alarm signal and photographic apparatus; Fig. 2 indicates an enlarged vertical section of a portion of Fig. 1; Fig. 3 shows an enlarged fragmentary portion of Fig. 1; Fig. 4 represents an enlarged elevation of some detail; Fig. 5 is a right hand view of Fig. 4; Fig. 6 shows a wiring diagram of the apparatus; Fig. 7 indicates an enlarged vertical axial section of the upper portion of Fig. 1 with parts in full lines; Fig. 8 indicates a top view and section of Fig. 7 on the line 8, 8; Fig. 9 shows a bottom view of a portion of Fig. 7; Fig. 10 is a section of Fig. 9 on the line 10, 10; Fig. 11 shows an enlarged fragmentary portion of Fig. 1; Fig. 12 represents an enlarged vertical section of a siren of the apparatus with portions in full lines; Fig. 13 shows an elevation of a detail; Fig. 14 indicates a sectional elevation of some details; Fig. 15 represents an enlarged rear view of the appurtenances of the fire signal alarm box of the apparatus; Fig. 16 shows an elevation of some of the elements indicated in Fig. 15; Fig. 17 is a section of Fig. 16 on the line 17, 17; Fig. 18 indicates an enlarged partial section of Fig. 1 on the line 18, 18, with portions shown in full lines; Fig. 19 is a right hand view of Fig. 18 with a partial section on the line 19, 19 of said Fig. 18 and Fig. 20 indicates a top view and section of Fig. 19 on the line 20, 20.

In the drawings the invention is indicated with a fire alarm post 20, which has formed therewith the fire alarm signal box 25, having hinged thereto the front door 30. The fire alarm signal box 25 is of the character described in United States Letters Patent to Frederick W. Cole, No. 553,839, dated February 4th, 1896. From the roof of the fire alarm signal box 25 extends the tubular pole 68. The turn table box 85 is mounted on the top end of the said pole 68. To the top of the turntable 127 is clamped the arm 71 and to the latter is adjustably secured the housing 180 of the signal and photographic apparatus.

Referring to Figs. 1, 3, 15, 16 and 17, the door 30 of the fire alarm signal box has connected to its rear face a signal device of the usual construction and comprises essentially the rear frame 31 supported on the posts 32 extending from the rear face of said door 30. An operating shaft 33 has its ends journaled in the frame 31 and the door 30. An operating handle 34 is fastened to one end of the shaft 33. A ratchet wheel 38 is journaled on the shaft 33 and has pivoted thereon the pawl 39. A ratchet wheel 40 is journaled on the shaft 33 and has formed therewith the four indents 41, that coact with the pawl 39. A spring 42 has one end attached to the ratchet wheel 40 and its other end is fastened to the door 30. An escapement 45 is pivoted between the door 30 and the frame 31. The escapement has extending therefrom the handle 46 with the clapper 47. A gong or bell 48 extends from the rear face of the door 30. A pawl 49 is pivoted to the door 30 and coacts with the ratchet wheel 38.

To the ratchet wheel 38 is fastened the contact making ring 55 having the four electric circuit breaking segments 56 of electric insulating material. The circuit breaking segments 56 divide the ring 55 into quadrants. A brush holder support 57 of electric insulating material is fastened to the rear face of the door 30 and has extending therefrom screws 58 for the caps 59. Brushes 60 bear on the support 57 and nuts 61 in threaded engagement with the screws 58 bear on the said brushes 60. Lead wires 230 and 232 encircle

the screws 58. The said brushes 60 are disposed with their ends in contact with the contact making ring 55.

From the top of the fire alarm signal box 5 extends the tubular pole 68 having the cap 69 and on the latter is supported the turntable box 85. The turntable 127, to be described, has detachably clamped thereto the tubular arm 71 which at its outer end has 10 extending therefrom the member 72 of a pair of clamps, and at the other end of the arm 71 is secured the ornamental counterweight 73. A sleeve 74 with the ball bearing race 75 is fastened to the pole 68. A sleeve 76 with the ball bearing race 77 is rotatably supported on the pole 68. The sleeve 76 has formed therewith the inclined member 78. A Y fitting 80 with the inclined sleeve 81 is fastened to the arm 71, and a tubular brace 82 connects the members 78 and 81. The ball bearing races 75 and 77 are provided with the ball bearings 83.

The turn table box 85, see Figs. 1, 7 and 8, is indicated to comprise the base plate 86 which is fastened to the cap 69 of the pole 68, by means of the screw bolts 87. To and below the base plate 86 is fastened the bottom wall 88 of the turntable box 85. Vertical side walls 89 extend from the bottom wall 88, and are connected or join with the front wall 90 and the rear wall 91. A top wall or cover 92 having the opening 93 is detachably supported on said side walls and the said front and rear wall. A base plate 95 has extending therefrom the sleeve 96. The base plate 95 is fastened to the base plate 86 by means of the screws 97. A U shaped frame having the vertical members 100, 101 and the connecting portion 102 extends up 30 from the said base plate 95. A bearing face 103 is formed with the boss 104 that extends from the connecting portion 102. A worm shaft 106 with the worm 107 is journaled in the member 100 and 101. A sprocket chain 40 wheel 108 is fastened to the worm shaft 106. A shaft 112 is rotatably supported at one end in the sleeve 96 and has fastened thereto the worm wheel 113, which meshes with the worm 107. An electric motor 118 is indicated with the feet 119 and the latter are 50 fastened to the base plate 86 by means of the screw bolts 120. The armature shaft of the electric motor is indicated at 121. A sprocket chain wheel 122 is fastened to the armature shaft 121 and a sprocket chain 123 connects the sprocket chain wheels 108 and 122.

To the top end of the shaft 112 (see Figs. 1, 7, 9, 10, and 11), is fastened the boss 126 of the cup shaped turntable 127. A disc of 60 electric insulating material 128 is fastened to the lower face of the top wall of said turntable, by means of the screws 129. A pair of concentric contact rings 132 and 133 are fastened to the disc 128 by means of the screws 134 and 135. Insulating sleeves 136 and 137

extend through the top wall of the turntable and contact with the disc 128. A screw 138 extends through an opening in the sleeve 136, and its lower end is in threaded engagement with the contact ring 133. A binding cap 139 is in threaded engagement with the upper end of the screw 138. A screw 140 extends through an opening in the sleeve 137 and its lower end is in threaded engagement with the contact ring 132. A binding cap 141 is in threaded engagement with the upper end of the screw 140. The screws 138 and 140 with their appurtenances constitute binding posts. A wire 237 extends from the screw 138, and a wire 238 extends from the screw 140.

Similar brackets 151 and 152 extend from the portion 102. Each of the brackets 151 and 152 carry a ring comprising the portions 153 and 154 of electric insulating material. A hollow plug 155 having a cavity 156 is shown with the threads 157 on its outer circumferential surface. A cylindrical barrel 162 closed at its lower end is indicated with the interior thread 163. The latter is in threaded engagement with the threads 157 of the plug 155. The barrel 162 bears up against the ring portion 154 and is tightly clamped thereto. The lower end of each barrel 162 has in threaded engagement therewith the binding screw 165. A wire 235 for electric current extends from one of the screws 165 and a wire 236 extends from the other screw 165. In the plugs 155 are respectively positioned the brushes 168 and 169. A spring 170 in each plug 155 bears up against the brush therein. The brush 168 bears against the ring 132 and the brush 169 bears against the ring 133.

A pair of similar clamps 176 (Figs. 1 and 11) are positioned above the turntable 127. Bolts 177 extend through said clamps and the said turntable. The said clamps 176 bear on the arm 71 and detachably clamp the latter to the turntable 127. Nuts 178 are provided for the bolts 177.

The housing 180, see Figs. 1, 18, 19 and 20 of the signal and photographic apparatus is indicated to comprise the front wall 181, having the openings 182 and 183, the rear wall 184, the side wall 185, the side door 186, the top wall 187 and the bottom wall 188. A hood 189 extends from the front wall 181 for the opening 183. A magnifying lens 190 extends from the front wall 181 over the opening 182. A clamping member 193 extends from the top wall 187 and is adjustably secured to the clamping member 72 by means of the bolt 194.

A siren (see Figs. 12, 18, 19 and 20) is indicated in its entirety by the numeral 195 and is similar to the siren described in our patent application for fire alarm signal and photographic devices, filed April 15, 1929, Serial Number 355,344. The said siren is shown with the central shaft 196, to which is fastened the usual armature 197 of an electric

motor. At the upper end of the siren is supported the gear housing 198. The shaft 196 extends into the gear housing 198 and has fastened thereto the worm 199. A spindle 200 is journaled in the housing 198, and has fastened thereto the worm wheel 201, which latter meshes with the worm 199. On the spindle 200 is fastened the pulley 202. A pair of wires 237 and 238 lead to the field 204 of the electric motor in the siren. A base plate 205 is fastened to the wall 188 and the lower portion of the siren is supported upon and fastened to said base plate. The siren 195 is shown with the cylindrical housing 206 having the enlarged lower portion 207 with the openings 208. The top wall of said housing is shown at 209 having the openings 210 and the hub 211 with the bushing 212. A propeller wheel 213 is shown with a hub 214 which is fastened to the shaft 196. A supporting disc 214^a is detachably supported in the housing 206. A moving picture camera is indicated in its entirety by the numeral 215. The operating shaft 216 of the camera has fastened thereto the pulley 217, and a belt 218 connects the pulleys 202 and 217. A rubber hood 219 extends from and over the lens holder of the camera 215 and bears against the rear face of the wall 181. The lower end 30 of the camera is provided with the dove tail projection 221 which is in slidably engagement with the guide strips 222 that extend from the base plate 205. An electric light bulb socket 223 is fastened to the base plate 205 and has detachably fastened thereto the electric light bulb 225. The electric light bulb 225 is located in line with the lens 190. A reflector 226 is positioned behind the electric light bulb 225 and is supported by the bracket 227 extending from the base plate 205.

Referring particularly to Fig. 6 the ratchet wheel of the fire alarm signal box 25 is indicated at 38 and the brushes are shown at 60. The electric motor 118 and the member 100 for the turntable box 85 are shown. The turntable is indicated at 127. The camera is indicated at 215, the siren is shown at 195, and the electric light bulb is shown at 225.

Lead wires from a source of electric current are shown at 230 and 231. The wire 230 leads to one of the brushes 60. From the other brush 60 extends the wire 232. From the wire 232 extends the wire 234 which latter leads to one of the poles of the electric motor 118. The wire 231 leads to the other pole of said electric motor. From the wire 231 extends the wire 235 which leads to the brush 169. From the wire 234 extends the wire 236 which leads to the brush 168. From the screw 138 extends the wire 237, which leads to one of the poles of the electric motor of the siren 195. From the screw 140 extends the wire 238, which leads to the other pole of the electric motor of the siren. From the wire 238 extends the wire 239 which leads

to the socket of the electric light bulb 225. A wire 240 extends from the wire 237 and also leads to the socket of the electric light bulb 225.

To operate the fire alarm signal and photographic apparatus the handle 34 is turned in the direction of the arrow in Fig. 3 until the gong 48 rings. Thereby the ratchet wheel 38 is turned one quarter of a revolution and makes electric contact with a quadrant of the contact making ring 55. The electric contact is broken when the next electric circuit breaker 56 is reached. By closing the electric circuit with the turning of the handle 34 the electric motor 118 is energized and through its connections, the turntable 127 is turned one revolution, which swings the tubular arm 71. At the same time the housing 180 of the signal and photographic apparatus is revolved around the pole 68 and the lens 190 of the moving picture camera 215 is focused on the fire alarm signal box 25, and thereby any person in the vicinity of said box is photographed. At the same time the armature shaft 196 in the siren 195 is turned and an audible signal is produced. With the rotation of the shaft 196, and by means of the pulleys 202, 217 and the belt 218, the moving picture camera 215 is operated.

Various modifications may be made in the invention and the present exemplification is to be taken as illustrative and not limitative thereof.

Having described our invention what we desire to secure by Letters Patent and claim is:

1. In an apparatus of the character described, the combination of a fire alarm signal box, means connected to the fire alarm signal box to operate the same, an electric circuit, means for closing said circuit operated by the operation of the fire alarm signal box, an arm supported above said box, means included in said circuit to revolve said arm, photographic means carried by said arm and means to operate said photographic means when said electric circuit is closed.

2. In an apparatus of the character described the combination of a fire alarm signal box, means connected to the fire alarm signal box to operate the same, an electric circuit, means for closing said circuit operated by the operation of the fire alarm signal box, an arm supported above said fire alarm signal box, means included in said circuit to revolve said arm, a motion picture camera supported by the arm and means interposed between said fire alarm signal box and said motion picture camera to operate the latter when said electric circuit is closed.

3. In an apparatus of the character described the combination of a fire alarm signal box, a pole extending upwardly from said box, an electric motor supported at the top end of said pole, a pair of lead wires for

- electric current leading to said fire alarm signal box, means connected to said box to close the electric circuit in said lead wires when the box is operated, said motor 5 energized by the circuit in said wires, a turntable, driving connections between the turntable and said electric motor, an arm supported on said turntable, a housing suspended from said arm, a motion picture camera supported in said housing, an electric light bulb supported in the housing, a siren supported in the housing, an electric motor in said siren to operate the same, the latter motor and electric light bulb energized with the 10 closing of said electric circuit and driving connections between the siren and camera to operate the latter during the operation of the siren.
4. In an apparatus of the character described 15 the combination of a fire alarm signal box, a wheel journaled in said box, a contact ring fastened to said wheel, circuit breaking segments in said ring, means to turn the wheel when operating said box, 20 brushes bearing on the contact ring, lead wires from a source of electric current in connection with said brushes, an electric motor supported in the apparatus, said lead wire extending to said electric motor, a turntable 25 adjacent to said electric motor, means to turn the turntable when said motor rotates, a pair of contact rings fastened to the turntable, brushes bearing against the latter contact rings, wires connecting the latter 30 35 brushes and said lead wires for electric current, an arm fastened to the turntable, a housing suspended from said arm, a siren, a camera and an electric light bulb supported in said housing, an electric motor having a shaft journaled in said siren, the latter motor in electric circuit with said last mentioned brushes, said electric light bulb in electric circuit with said last mentioned brushes and means interposed between said 40 45 siren and said camera to operate the latter with the turning of the shaft in said siren.
- Signed at Bayonne in the county of Hudson and State of New Jersey this 17th day of May, A. D. 1930.
